4 Claims. (Cl. 103—130)

So-called "cycloidal pumps" are known, where an internal pinion or gear formed with curve-shaped teeth is rolling on at a corresponding internal tooth with a number of teeth greater by one in such a manner that the teeth of the pinion and those of the ring gear are in meshing engagement on one side and touch head to head on the opposite side thereof. With known pumps of this type, the pinion is keyed to the driving shaft which is rotating eccentrically relatively to an internal ring gear in the casing. On each rotation of the shaft the ring gear is rotated further by one width of tooth relative to the shaft. Between the internal teeth of the ring gear and the teeth of the pinion chambers are provided which on the one side of the plane defined by the central axes of the ring gear and the driving shaft continually increase in size and on the other side of such plane continually decrease in size. If a controlling slide valve is provided connecting the chambers on the one side with a suction line and on the other side with a pressure line, the rotation of the shaft causes fluid to be drawn from the suction line and fed to the pressure line. The pressures obtainable with a pump of this type presently depend on the tightness of engagement between the teeth of the ring gear and that of the pinion. Since this involves a positive guide of the pinion in the ring gear, this tightness is dependent on the accuracy of the fit. Now, the pinion is additionally mounted on the driving shaft so that a kinematic redundancy of determination exists which might lead to jammings if the tolerances provided are not relatively great. A further difficulty stems from the fact that with known cycloidal pumps the pinion is rotating with the full driving speed since it is carried along with the driving shaft, being keyed thereto. Therefore, it rolls about the internal teeth with a relatively high peripheral speed leading to considerable strain on the parts. For this reason, cycloidal pumps of the type described, despite various favorable properties have only been in practical use to a limited extent and have been applied only under conditions where particularly high pressures are not of much importance. By way of example, such a pump has been proposed as filling pump for hydrostatic axial piston transmissions.

It is the object of the present invention to design a cycloidal pump of the aforementioned type so as to avoid this kinematic redundancy of determination and so that the relative movement between the pinion and the ring gear takes place with less peripheral speed.

According to the invention this object is being attained by providing that the pinion is freely rotatably supported on an eccentric hoop, with the ring gear being stationary. The hoop in turn is eccentrically and rotatably supported on an internal eccentric rotating about the center of the ring gear in such a manner that the eccentric hoop executes a circular movement about the center point of the ring gear and causes the pinion to roll thereat. In this arrangement, the double-eccentric support of the pinion permits an alignment of the pinion relative to the ring

2

gear. An additional degree of freedom is provided, thereby avoiding the possibility of redundancy of determination and of jamming. In accordance with the rolling in the ring gear the pinion may rather freely adjust or let 5 vary its eccentric point, without being disturbed from the side of the drive axis. Besides, the high rates of relative peripheral speed are dispensed with, being replaced by the eccentric movement which has only a very small path.

An embodiment of the invention is presented in the drawings and described as follows:

FIG. 1 is a perspective view of a pump of the invention, wherein some parts are shown broken away.

FIG. 2 is a cross-sectional view and

FIG. 3 a longitudinal sectional view of the pump.

FIG. 4 is a perspective view of the eccentric hoop and FIGS. 5 and 6 illustrate the kinematic conditions and those of forces in the pump of the invention.

Reference numeral 1 designates an external rim defining a ring gear stationarily arranged in the casing 1. Ring gear 1 is provided with internal teeth 2 formed with curve-shaped teeth. A gear or pinion 3 engages the teeth of ring gear 1 with the center of the pinion orbiting about the center of the ring gear. The teeth spaces of the pinion correspond in shape to the teeth 2 of the ring gear, and the teeth of the pinion substantially correspond to the teeth spaces of the ring gear so that the pinion and ring gear will snugly engage each other. The number of teeth of pinion 3 is one less than that of ring gear 1. The teeth are so designed that pinion 3 is in meshing engagement with the internal teeth 2 at a point 4, whereas the teeth of the ring gear and pinion touch head to head at another point 5. Thus, pinion 3 is completely positively guided in the internal teeth 2. On movement of pinion 3 about the internal teeth 2 a small shift of pinion 3 is effected. When the center of pinion 3 has made one orbit about the center of ring gear 1, the pinion is shifted by one tooth width. In the embodiment described the ratio of the number of teeth is 13:14. Consequently, pinion 3 has made one full turn after its center has orbited about the center of the ring gear 2 thirteen times. Pinion 3 is mounted on an eccentric hoop 6. Hoop 6 has a central opening 7 defining a circular inner surface 7' formed about an axis 7" which (FIG. 4) is arranged eccentrically to a circular outside surface 8 thereof upon which gear 3 is mounted. With this central opening 7 the hoop 6 is mounted on an eccentric 9 which rotates about an axis 10. Eccentric 9 has an axis 9" which corresponds to axis 7" of opening 7. Note in FIG. 1, that the eccentric 9 is arranged on a hollow shaft 12 being formed with a cylindrical insertion 11 at the inside thereof. This hollow shaft 12 is carried along with a driving shaft by means of splines 13 and journaled in casing 1' in a ball bearing 12'. Laterally, the pump chambers are sealed by annular bodies 14, 15.

Pinion 3 is formed with radial bores 16 between all teeth (FIG. 2). The eccentric hoop 6 possesses crescent shaped recesses 17, 18 so that the surface 8 provides a controlling slide valve in which the bores 16 terminate. The recess 17 communicates with an annular chamber 20 through axial bores 19 (FIG. 4), which chamber connects to a fluid inlet 20' of casing 1' and wherefrom the fluid shall be sucked in. The recess 17 therefore provides the suction side of the controlling slide valve. Recess 18 connects to a crescent shaped recess 22 of the internal eccentric 9 through radial bores 21. This again connects to a central fluid outlet channel or chamber 23'

within the hollow shaft 12 through radial channels or chambers 23 of the internal eccentric 9.

On drive of the internal eccentric 9 pinion 3 successively engages the internal teeth 2 in such a degree as the plane A—A rotates. Plane A—A is defined by the central axis 10 of ring gear 1 and axis 8' of eccentric hoop 6. On rotation in clockwise direction (arrow 24 in FIG. 2) the chambers between the teeth of pinion 3 and that of ring gear 1 on the right side of plane A—A decrease, while on the left side thereof they increase in size. Therefore, fluid is sucked into the left chambers whereas the fluid is forced out of the right chambers. Note, that the expressions "right" and "left" refer to the existing condition illustrated in FIG. 2. The plane A—A is rotating with the eccentric 9 and the eccentric hoop 6. With this plane A—A the controlling slide valve is also rotating being provided by the eccentric hoop 6. Therefore, the recess 17 always connects to the chambers increasing in volume, through the channels 16, whereas the recess 18 always connects to the chambers decreasing in size. Therefore, oil or other fluid is sucked in through the openings or channels 19 from chamber 20 into the recess 17 and the "left" chambers on the suction side. Upon further rotation of the eccentrics 9, 6 such fluid, e.g., oil is forced into the recess 18, then inwardly through channels 21, recess 22 and channels 23 and out through the outlet channel 23'.

The two eccentrics 9 and 6 have the same effect as a crank, as is illustrated in FIG. 5 or 6, it being imagined that the crank 9' is driven in the direction of the arrow 27 and the pinion 3 is supported as at 8'. The axis 9'' of the eccentric corresponds to the axis 7'' of the central opening 7 of hoop 6. It can be seen that the distance a is variable so that the pinion obtains an additional degree of freedom. It may therefore adapt to the internal teeth of the ring gear, without its support on the double eccentric 6, 9 interfering in some way.

If there were no friction existing, the eccentrics 9 and 6 would be favorably designed as to lead to the conditions illustrated in FIG. 5. The oil pressure on the pressure side of the controlling slide valve (recess 18) exerts a force P perpendicular to plane A—A, that is to say, perpendicularly to the plane A—A through the central axis 25 of ring gear 1 (which corresponds to the axis 10 of rotation of the eccentric 9) and the central axis 26 of the outside surface 8 eccentric hoop 6 (which corresponds to the central axis 8' of gear 3). The friction being negligible this force P would, in the arrangement according to FIG. 5, align with the longitudinal dimension of lever 6'.

Different conditions prevail if the friction must be taken into consideration. On rotation of the eccentric in clockwise direction (arrow 27), the friction exerts a force P' which produces a torque in counterclockwise direction and being proportional to the contact pressure P. With such force the teeth would be pressed head on head in point 5 (FIG. 2) with an arrangement according to FIG. 5. Even though a certain contact pressure between the teeth in point 5 is desirable so as to obtain a good sealing between pressure and suction side, undesirable wear might, however, occur with excess of contact pressure. In FIG. 6 the lever 6' is therefore somewhat inclined relatively to plane A—A so that the lines of connection of the center points of internal teeth 2 and eccentric hoop 6 on the one hand (25 and 8' respectively) and of eccentric hoop and internal eccentric on the other hand (8' and 9'' respectively) constitute an obtuse angle 30. Thereby, it is achieved that the resultant R of P and P' again aligns with the longitudinal dimension of lever 6'. In such case, no contact pressure would occur. Of course, through adequate inclination of lever 6' a certain contact pressure between the teeth may be maintained. If desired, it may also be possible to make the lever 6' incline to the other side so as to achieve a particularly

strong contact pressure between pinion 3 and internal teeth 2.

For the purpose of balancing the eccentric pinion 3 the eccentric hoop 6 is provided with extensions 28 (FIGS. 3 and 4) on one side.

I claim:

1. In an internal gear machine having a stationary ring gear with a given number of internal teeth concentric with a first axis, a rotatable pinion having one less than said number of teeth to mesh with those of the ring gear, said pinion being adapted to orbit about said axis with its teeth in meshing engagement with the internal teeth at one side and touching head to head on the other side, said pinion having a central opening concentric with the axis of the teeth thereof, and a shaft extending through said opening and mounted for rotation concentric with the first axis, the improvement comprising: said shaft having an eccentric fixed thereto with a cylindrical outer face eccentric to the first axis; and a hoop between said eccentric and said pinion and rotatable with respect to each, said hoop having an outer surface formed about one axis and an inner surface formed about another axis, said inner surface being in supporting contact with the eccentric face and said outer surface being in supporting contact with the interior of said pinion at said opening, whereby the pinion is provided with an additional degree of freedom to better enable it to provide said head to head contact at said other side in a fluid sealing manner while engaging the ring gear at said one side.

2. In a machine as set forth in claim 1, the improvement comprising: said pinion having bores extending radially between said teeth thereof to the inner opening therein, said hoop having conformations about the exterior thereof defining a controlling slide valve.

3. In a machine as set forth in claim 2, wherein said conformations define two crescent shaped peripheral recesses on the hoop, said hoop having a radial bore communicating with one of the recesses, said eccentric having a radial bore and passageway means communicating with the hoop bore at a given position of the hoop on the eccentric.

4. An internal gear pump including: a stationary ring gear with a given number of internal teeth concentric with a first axis; a rotatable pinion having one less than said number of teeth to mesh with those of the ring gear, said pinion having teeth and being adapted to orbit about said axis with its teeth in meshing engagement with the internal teeth at one side and touching head to head on the other side, a central opening in said pinion defining a bearing face and bores in said pinion extending from between the teeth to the central opening; a hoop within said opening, said hoop having a circular outer surface and a circular inner surface formed about spaced axes, said outer surface being in supporting contact with said bearing face to rotatably support the pinion on the hoop, said hoop having two crescent recesses in the outer surface, said recesses being spaced circumferentially with each other and in alignment with the inner ends of said bores, said hoop having fluid channels extending from said recesses, shaft means including an inner eccentric secured thereto, said eccentric being within said hoop and in contact with said inner surface to rotatably support the hoop thereon; and casing means about said ring gear and fixedly supporting said ring gear and rotatably supporting said shaft means, said means defining an inlet chamber positioned to communicate with some of said channels at one rotational position of the hoop and a discharge chamber positioned at another rotational position of the hoop to communicate with others of said channels of the hoop, whereby as said shaft is rotated said eccentric and hoop cause said pinion to orbit about the ring gear and said hoop provides said pinion with an additional degree of freedom and serves as a slide valve to connect the spaces between the teeth of the ring gear and pinion at one side to said

inlet chamber and to connect said spaces at the other side to said discharge chamber.
